United States Patent Office

Des. 222,250
Patented Oct. 12, 1971

222,250

CHLORINATOR

Robert S. Lucas, Harbor City, Calif., assignor to
Purex Corporation, Ltd., Lakewood, Calif.

Filed June 29, 1970, Ser. No. 23,723

Term of patent 14 years

Int. Cl. D24—02; D23—01

U.S. Cl. D16—2

FIG. 1 is a perspective view of a chlorinator, showing my new design;

FIG. 2 is a front elevational view thereof;

FIG. 3 is a plan view thereof;

FIG. 4 is a side elevational view thereof taken along line 4—4 in FIG. 2; and

FIG. 5 is a rear elevational view thereof.

I claim:

The ornamental design for a chlorinator, substantially as shown.
